UNITED STATES PATENT OFFICE.

HENRY J. CHILTON, OF CHICAGO, ILLINOIS.

BAG HANDLE.

Application filed October 13, 1919, Serial No. 330,293. Renewed October 29, 1921. Serial No. 511,448.

To all whom it may concern:

Be it known that I, HENRY J. CHILTON, a citizen of the United States, residing at Chicago, in the county of Cook and State of Illinois, have invented a certain new and useful Improvement in Bag Handles, of which the following is a full, clear, concise, and exact description, reference being had to the accompanying drawings, forming a part of this specification.

The invention relates to handles for traveling bags and the like, and primarily to that type of these devices which has as its object the prevention of theft, unauthorized use or mistakenly appropriating the bag of another.

The invention has among its various objects the production of a construction whereby the handle may be so arranged that it may assume an inoperative and inaccessible position, rendering the handle inoperative as a means for carrying the bag. It is also an object to utilize a lock to lock the handle in either of its positions.

In addition the invention has as an object the provision of a fitting which is attached to a substantial portion of the bag frame, thereby eliminating any possibility of springing or otherwise distorting either of the frames, and which in itself has the required strength to withstand the strains exerted through the weight of various objects carried within the bag or other strains to which a handle is subjected.

The invention has as a further object the production of other fittings which cooperate with the above referred to fitting to securely hold same in position and which add to the appearance of the bag when the handle is in either of its positions, and which may be readily applied and cheaply produced.

The invention contemplates various details of construction and design which will result in greater strength, and which will add to the appearance thereof, all of which will be clearly understood when read in conjunction with the accompanying drawings and specification which describe the construction in detail.

In the drawings Fig. 1 is a side elevation of a bag having the invention applied thereto and being broken away to show a position which the handle may assume when in an inoperative position;

Fig. 2 is a sectional view taken on line 2—2 of Fig. 1;

Fig. 3 is a sectional view taken on line 3—3 of Fig. 2;

Fig. 4 is a plan view partially in section showing one of the fittings used in the construction shown in Fig. 1; and

Fig. 5 is a detail perspective view of the portion which is secured to the bag and to which the handle is secured so as to permit same to assume various positions, as shown in Fig. 1.

The invention contemplates the use of a pair of fittings generally designated 10 and 11, which are spaced apart from each other and have one end connected to the bag handle, the opposite ends of said fittings being secured to this bag frame 12 so that the entire strain will be exerted upon this frame and none will be transmitted to the smaller frame 13. Thus this smaller frame which usually carries the elements which cooperate with the lock 14 and catches 15—15, will not become distorted as would result should any strain be transmitted thereto. These fittings 10 and 11 each have a portion which is designed to be arranged or interposed between the bag frames 12 and 13 when said frames are closed as shown in Fig. 2, yet permits these frames to be opened to permit of access to the interior of the bag or to permit the handle to be arranged within the bag and locked therein by means of the key lock 14 and the catches 15—15 usually provided upon traveling bags. These fittings generally designated 10 and 11 include the swinging elements 16, the depending arms 17—17 and the attaching element 18, the latter being arranged upon the outside of the larger bag frame and has the clamping fingers which extend through apertures in this frame and engage the arms 17—17 and securely hold the latter with relation to the frame 12 which carries all of said fittings.

This attaching element 18 is preferably stamped to produce the body portion 18^a which is of a length sufficient to extend to the apertures 19—19 usually provided in frames for the reception of the holding elements of fittings ordinarily provided for holding the handle to the frames. As before stated, these elements 18 are provided with fingers 20—20 which are passed through the apertures 19—19 in the frame, and through the apertures 21—21 provided in the laterally projecting portion 22 of the depending arms 17, they being bent as shown to clamp these arms to the frame. The upper

wall of these elements 18 is curved transversely of the length of the frame or in other words to correspond to an arc struck from the center of the pivot of the swinging element 16. This is clearly shown in Fig. 2. The element 16 is pivoted between these depending arms by means of the pin 23 which has its ends headed or upset to prevent separation of these parts. This pivoted element has an eyelet 24 for the reception of the pin and a shank portion 25 which extends from the eyelet to the transverse portion 26 which is of a length sufficient to extend beyond the edge 27 of the frame 12, at which point it is bent to produce the hook shaped portion 28, the latter being separated from the transverse portion 26 so that it may be passed over the frame 12 and over the element 18 when the handle is swung to either of its positions. For the purpose of affording strength to the member 16 at the bend 29 it is arched as clearly shown in Fig. 4, and is of a greater dimension at this point than the shank 25. The hoop shaped portion 28 is curved in both directions, that is from one side edge to the other and from the bend 26 to the extremity of the hook portion. This construction results in a housing for the reception of the bent ends of the fingers 30-30 of the eyelet 31, whereby the ring 32 of the handle is secured to this fitting. By curving the hooked portion in the manner specified its strength is increased and its appearance added to when the handle is arranged in carrying position. The curve of the side edges of the hook shaped member preferably corresponds to an arc struck from the center of the pin 23 and is spaced apart from the member 18 a distance sufficient to permit same to clear said member.

From the foregoing explanation of the structure it is evident that no strain of any kind is transmitted to the smaller frame 13, as the fittings are secured to the larger frame 12. The transverse portion 26 being interposed between the frames 12 and 13 transmits any strain directly upon the larger frame 12. By resorting to this arrangement the smaller frame is protected against being distorted, which insures that the alignment of the portions which cooperate with the lock 14 and catches 15-15 is insured, as these parts are usually carried by the smaller frame 13.

It is further evident that the parts are designed so that the material is distributed and proportioned in a manner which insures the proper strength of the parts and also that the same may be stamped which results in that it may be cheaply manufactured. It is also evident that the fingers 30-30 of the eyelet 31 are housed so that same cannot contact with anything when the fitting and handle is swung into or out of the bag.

Having thus described the invention it is

obvious that changes and modifications may be resorted to without departing from the spirit of the appended claims.

What I claim and desire to cover by Letters Patent is:

1. In a handle for traveling bags constructed to be positioned interiorly and exteriorly of the bag, the combination of a fitting, a frame to which the fitting is secured, said fitting having a handle secured thereto and being mounted to swing over the frame and being reenforced between the connection with the frame and the handle, the fitting being curved to correspond with an arc struck from the center of its pivot and being curved lengthwise of the frame.

2. In a handle for traveling bags constructed to be positioned interiorly and exteriorly of the bag, the combination of a fitting, a frame to which the fitting is secured, said fitting having a handle secured thereto and being mounted to swing with relation to the frame, means for attaching said fitting to said frame, said means and said fitting being curved to correspond with the curve of an arc struck from the pivot of said fitting.

3. In a handle for traveling bags constructed to be positioned interiorly and exteriorly of the bag, the combination of a fitting constructed to swing from the interior to the exterior of the bag, a handle secured to the fitting, a frame to which said fitting is secured, said fitting being reenforced between its connection with the frame and the handle, means for securing the fitting to said frame, said means including a pair of arms depending from the frame and means connecting said arms to the frame.

4. In a handle for traveling bags constructed to be positioned interiorly and exteriorly of the bag, the combination of a handle, a fitting whereby the handle is secured to the bag, a frame to which the fitting is secured, said fitting being mounted to be passed over the frame to position the handle interiorly or exteriorly of the bag, and being curved lengthwise and transversely of said frame.

5. In a handle for traveling bags constructed to be positioned interiorly and exteriorly of the bag, the combination of a fitting, a frame to which the fitting is secured, a handle and means for attaching the handle to the fitting, said fitting being constructed to provide a space between it and the frame to allow said means to be arranged between the fitting and the frame.

6. A handle for traveling bags constructed to be positioned interiorly and exteriorly of the bag, the combination of a fitting, a frame to which the fitting is secured, a handle, and means for attaching the handle to the fitting, said fitting being curved lengthwise and transversely of the frame to provide a

housing between said frame and said fitting.

7. In a handle for traveling bags constructed to be positioned interiorly and exteriorly of the bag, the combination of a fitting, a frame to which the fitting is secured, a handle secured to the fitting, said fitting being mounted to swing over the frame interiorly and exteriorly of the bag, said fitting being reenforced between the connection with the frame and the handle, and being curved to correspond with an arc struck from the center of the pivot of said fitting.

8. In a handle for traveling bags constructed to be positioned interiorly and exteriorly of the bag, the combination of a fitting constructed to swing from the interior to the exterior of the bag, a handle secured to the fitting, a frame to which said fitting is secured, and means for attaching said fitting to the frame, said means and said fitting being curved to correspond with the curve of an arc struck from the pivot of the fitting and said fitting being curved lengthwise of the frame.

9. In a handle for traveling bags constructed to be positioned interiorly and exteriorly of the bag, the combination of a frame, a fitting constructed to swing with relation to the frame, a handle secured to the fitting, attaching means for attaching the handle to the fitting, said fitting being curved to correspond with the curve of an arc struck from the pivot of the fitting and being also curved lengthwise of the frame to provide a housing for the handle attaching means, means for securing the fitting to the frame, said means including a portion arranged outside of the frame and having a portion which is curved transversely to its length.

10. In a handle for traveling bags constructed to be positioned interiorly and exteriorly of the bag, the combination of a handle, a fitting whereby said handle is secured to the bag, said fitting being pivoted to swing interiorly and exteriorly of the bag and having a portion which is curved to correspond with an arc struck from the center of the pivot of said member.

11. In a handle for traveling bags constructed to be positioned interiorly and exteriorly of the bag, the combination of a handle, a fitting whereby said handle is secured to the bag, and a frame to which the fitting is secured, said fitting being mounted to be passed over the frame to position the handle interiorly and exteriorly of the bag and being reenforced between the connection with the frame and the connection of the handle.

12. In a handle for traveling bags constructed to be positioned interiorly and exteriorly of the bag, the combination of a pair of frames, one of which is arranged

outside of the other, a fitting secured to the outer frame, a handle secured to said fitting, means for securing the fitting to the frame, and said fitting being constructed to permit the handle to be arranged interiorly and exteriorly of the bag.

13. In a handle for traveling bags constructed to be positioned interiorly and exteriorly of the bag, the combination of a pair of frames, one of which is arranged outside of the other, a fitting secured to the outer frame, a handle secured to said fitting, means for securing the fitting to the frame, said fitting being constructed to permit the handle to be arranged interiorly and exteriorly of the bag and a lock for locking said frames together.

14. In a handle for traveling bags constructed to be positioned interiorly and exteriorly of the bag the combination of a pair of frames, one of which is arranged outside of the other, a fitting having a handle secured thereto, said fitting being secured to the outer frame and being constructed to permit the handle to be arranged interiorly and exteriorly of the bag and a lock for locking the frames together when the handle is in either of its positions.

15. In a handle for traveling bags constructed to be positioned interiorly and exteriorly of the bag, the combination of a pair of frames one of which is arranged outside of the other, a fitting having a handle, said fitting being secured to the outer frame and constructed to permit the handle to be arranged interiorly and exteriorly of the bag and a lock for locking the frames together when the handle is arranged within the bag.

16. In a handle for traveling bags constructed to be positioned interiorly and exteriorly of the bag, the combination of a pair of frames, one of which is arranged outside of the other, a pair of fittings secured to the outer frame, a handle, the opposite ends of which are secured to said fittings, said fittings permitting said handle to be arranged interiorly and exteriorly of the bag and a lock for locking the frames together, said lock being arranged between said fittings.

17. In a handle for traveling bags, the combination of a pair of frames, one of which is arranged outside of the other, and a handle secured to the outer frame, said handle being permitted to be positioned interiorly and exteriorly of the bag and being constructed to permit the inner frame to be moved with relation to the outer frame and the handle.

18. In a handle for traveling bags, the combination of a pair of frames one of which is arranged outside of the other, and a handle secured to the outer frame, said handle being permitted to be positioned in-

teriorly and exteriorly of the bag and being constructed to permit the inner frame to be moved with relation to the outer frame and the handle, and means for locking said frames together when said handle is arranged interiorly or exteriorly of said bag.

19. In a handle for traveling bags, the combination of a pair of frames arranged 10 to be opened to permit of access to the interior of the bag and closed to prevent access thereto, a lock and a latch for releasably locking the frames together, a handle secured to one of said frames and having 15 means permitting the handle to be arranged interiorly and exteriorly of said bag, and being arranged to transmit the load upon the frame to which said handle is secured.

20. In a handle for traveling bags, the combination of a pair of frames arranged 20 to be opened to permit of access to the interior of the bag and closed to prevent access thereto, a lock for locking said frames together, a handle secured to one 25 of said frames and having means permitting the handle to be arranged interiorly and exteriorly of said bag, and being arranged to transmit the load upon one frame only.

30 21. In a handle for traveling bags, the combination of a pair of frames arranged to be opened to permit of access to the in-

terior of the bag and closed to prevent access thereto, a handle secured to one of said frames and having means permitting 35 the handle to be positioned interiorly and exteriorly of the bag, and arranged to transmit the load upon the frame to which said handle is secured.

22. In a device of the class described, the combination of a bag constructed to be opened to permit of access to the interior of said bag, and closed to prevent access thereto, a handle secured to the bag, said handle having means for permanently securing the handle to the bag and permitting the handle to be arranged interiorly and exteriorly thereof, said means being secured to the bag and having a portion constructed to be passed over and under the 50 portion of the bag to which it is secured.

23. In a device of the class described, the combination of an outer frame, a pair of fittings secured to said frame, a handle the opposite ends of which are secured to said 55 fittings, a lock arranged between said fittings, and a latch arranged upon the opposite sides of the lock, said fittings permitting the handle to be arranged interiorly or exteriorly of said bag.

In witness whereof, I hereunto subscribe my name this 8th day of October A. D., 1919.

HENRY J. CHILTON.
